L. FRANKLIN,
FREIGHT CAR DOOR,
APPLICATION FILED APR. 27, 1921,

1,424,292.

Patented Aug. 1, 1922.

L. Franklin, Inventor

By *Cashmore & Co.* Attorney

UNITED STATES PATENT OFFICE.

LEON FRANKLIN, OF EVANSVILLE, WISCONSIN.

FREIGHT-CAR DOOR.

1,424,292.

Specification of Letters Patent. Patented Aug. 1, 1922.

Application filed April 27, 1921. Serial No. 464,966.

To all whom it may concern:

Be it known that I, LEON FRANKLIN, a citizen of the United States, residing at Evansville, in the county of Rock and State 5 of Wisconsin, have invented a new and useful Freight-Car Door, of which the following is a specification.

This invention relates to doors for freight cars, one of its objects being to provide a 10 sliding door having a novel form of fastening means combined therewith whereby the door can be securely held in any position to which it may be moved, said door being caused to maintain its position no matter to 15 what extent it may be jolted.

A further object is to so mount the door that it can be moved freely upon its supporting rail and will not become detached therefrom.

20 A still further object is to provide door holding means which can be operated readily and which are constantly within convenient reach of a person beside the car.

With the foregoing and other objects in 25 view which will appear as the description proceeds, the invention resides in the combination and arrangement of parts and in the details of construction hereinafter described and claimed, it being understood that, within 30 in the scope of what is claimed, changes in the precise embodiment of the invention shown can be made without departing from the spirit of the invention.

In the accompanying drawings the preferred form of the invention has been 35 shown.

In said drawings

Figure 1 is a side elevation of a portion of a box car showing the present improvements combined therewith.

Figure 2 is a section on line 2—2, Figure 1.

Referring to the figures by characters of reference 1 designates a portion of a car 45 having brackets 2 outstanding therefrom above the door opening 3 and supporting a rail 4 which is L-shaped in cross section as shown in Figure 2. Mounted on this rail are supporting wheels or rollers 5 the peripheral portions of which are rounded or "crowned", each of these wheels being journaled within a yoke 6 formed at the upper end of a hanger 7. The hangers extend along the outer sides of the rail 4 and are 55 attached to the outer faces of the door 8 so as thus to support the door from the rail 4.

Holding brackets 9 are attached to the inner sides of the door 8 and extend over the top edge of the door and close to the inner side of the rail 4, thus to prevent the hangers 7 60 from shifting laterally and becoming disengaged from the supporting rail. Extending along the side of the car and parallel with the bottom of the door opening 3 is a rail 10 which is spaced from the wall of 65 the car a distance slightly greater than the thickness of the door 8, the inner surface of this rail 10 being inclined upwardly and outwardly as shown particularly in Figure 2 and said rail being held firmly to the car 70 by means of brackets 11. Likewise, as shown in Figure 1, the ends of the rails 10 are inturned and fastened to the car as shown at 12.

Mounted on the door 8 is a supporting 75 link 13 and pivotally connected to the lower portion of this link is a lever 14 having a long arm constituting a handle and a short arm. The short arm of this lever has diverging links 15 extending downwardly 80 therefrom and pivotally attached, as at 16 to the ends of oppositely extending levers 17. These levers are fulcrumed, as at 18, upon the outer face of the door 8 and terminate in downwardly extending arms 19 85 which are wedge shaped as shown in Figure 2. The ends of these arms extend between the rails 10 and the door 8. A spring 20 connects one end portion of lever 14 to the pivot 16 of the adjacent lever 17 so that said 90 lever 14 is normally drawn toward the adjacent lever 17 with the result that the links 15 pull upwardly upon the lever 17 and force the wedge shaped ends of the arms 19 95 normally into engagement with the rail 10.

As the lower ends of the arms 19 are wedge shaped they will wedge into the space between the rail 10 and the door 8 thus to frictionally engage these parts and hold the door 8 firmly in any position to which it may be moved. When it is desired to shift the door it is merely necessary to pull upwardly on the handle portion of lever 14 and against the action of the spring 20. This will cause the links 15 to push downwardly on the lever 17 and cause the arms 19 to move upwardly out of frictional engagement with the rail 10. Consequently the door 8 can then be pushed to the right or to the left by means of the lever 14 or by 110 thrusting or pulling on the edge of the door and when the door has reached the desired

position it is merely necessary to release the lever 14. Spring 20 will promptly return the parts to their normal position, forcing the wedge shaped ends of the arms 19 tightly into the space between the rail 10 and the door 8 and securely fastening the door in place.

It is to be understood that this fastening means will hold the door securely under all 10 conditions and no jolting will loosen the door because the spring 20 is constantly thrusting the wedge shaped portions against the rail 10 and will automatically take up any play that may result.

15 What is claimed is:

The combination with a car structure and a rail parallel therewith and spaced therefrom, the inner face of the rail being inclined downwardly and inwardly towards 20 the car structure, of a sliding door sup-

ported between the rail and car structure, oppositely extending levers fulcrumed on the door, wedging members carried by and integral with the levers and normally projecting between the door and rail, an actuating lever supported by the door, link connections between said actuating lever and the oppositely extending levers, and a spring connected to one of the levers for holding the wedging members projected 25 into frictional engagement with the rail and door.

In testimony that I claim the foregoing as my own, I have hereto affixed my signature in the presence of two witnesses.

LEON FRANKLIN.
